Primary Examiner — Kelley A Donnelly(74) *Attorney, Agent, or Firm* — Sterne, Kessler, Goldstein & Fox P.L.L.C.(57) **CLAIM**

The ornamental design for a display stand, as shown and described.

DESCRIPTION

The patent or application file contains at least one drawing executed in color. Copies of this patent or patent application publication with color drawing(s) will be provided by the Office upon request and payment of the necessary fee.

The FIGURE is a top front perspective view of a display stand showing the claimed design.

The dot-dash broken lines in the FIGURE and the areas within the dot-dash broken lines show portions of the display stand that form no part of the claimed design.

1 Claim, 1 Drawing Sheet**(1 of 1 Drawing Sheet(s) Filed in Color)**(56)
